UNITED STATES PATENT OFFICE

JAY WILL LYSONS, OF NEW YORK, N. Y.

DISPENSING DEVICE

Application filed May 9, 1929. Serial No. 361,637.

The object of my invention is to provide a shaving brush appliance in the nature of a dispensing member for dispensing shaving cream from a container to a shaving brush.

5 One object of the invention is to provide a device of the character described adapted to be attached to the end of a tube of shaving cream and provided with a valve mechanism for controlling the dispensing passage by a single rotating movement. Another object 10 of the invention is to provide an adapter nipple whereby the device may be attached to different sized shaving cream tubes or containers.

15 Accordingly my invention is embodied in a brush appliance or dispensing device adapted to be attached to a tube of shaving cream and arranged as disclosed in the following specification read in connection with the accompanying drawing in which

20 Figure 1 is a vertical sectional view through the device showing the valve closed.

Figure 2 is a similar view showing the valve open.

25 Figures 3 and 4 are sectional views taken respectively on the lines 3—3 and 4—4 of Figures 1 and 2.

Figure 5 is a sectional view of the adapter nipple.

30 My shaving brush appliance is adapted to be attached to the usual commercial tube 10 of shaving cream having a dispensing neck 11. Inasmuch as the dispensing end and neck of the tube may vary more or less in accordance with the designs of different manufacturers, I provide an adapter nipple, Fig. 5, having a flaring threaded mouth 12 adapted to fit a standard make of tube. The nipple is further threaded exteriorly at 13 to fit the 35 shaving brush device irrespective of the dimensions of the tube. In other words, the device carrying or attaching portion 14 of the adapter will be standard, while the mouths will differ depending upon the dimensions of the tube.

40 In this manner the device may be standard for all size tubes.

45 Referring now to the other figures, the adapter supports a base member 15 having a central passage 16 and formed with a flange

17 forming a trough. The base carries a tooth 18 and is recessed to receive a base member 19 cemented or otherwise secured in the recess and provided with an offset dispensing passage 20 and a ninety degree circular slot or groove 21. The base member is also formed with an annular flange 22.

55 The passage of cream from the tube through the passages 16 and 20 are controlled by a valve head 23 to which there is secured a sleeve 24 having an annular flange 25 which rotates on the base 15 below the base member flange 22. The sleeve 24 has a tooth 26. The valve head 23 has an offset passage 27 and a pin 28 adapted to move in the aforesaid groove 21. The valve head carries a circular shaving brush 29. The valve head passage 27 leads to the interior of the brush.

60 In assembling the device, the base member 19 is dropped into the sleeve 24, the flange 22 resting on the flange 25. The member 19 is then placed on the base and may either be driven in tight in the recessed base or otherwise secured thereto in non-rotatable relation. Thereafter the head 23 is placed with 65 in the sleeve 24 with its pin 28 within the groove 21, and the head and the sleeve are then secured together in non-rotatable relation.

70 It will therefore be understood that after assembly the head 23 and sleeve 24 move together as one part with respect to the base and member 19, which latter two elements constitute another part. The two parts are locked together by the flanges 22 and 25 and 75 have a relative rotary movement of ninety degrees limited by the pin 28 moving in the groove 21.

80 The numeral 30 denotes a cap which fits frictionally on the head 23 and which is provided with a cut out or notch 31 which fits 85 down over the two teeth 26 and 18 as shown in Figure 3.

85 From the foregoing it will be clear that the assembled device is attached to the tube by screwing the adapter on to the latter and then screwing the device on to the adapter. When thereafter the head is turned so as to bring the two teeth into alinement, the cap 90 may be affixed and pushed down into position, 95 100

the notch 31 fitting over the teeth. In this position, Figure 1, the valve head 23 is locked with respect to the base and the upper passage 27 is cut off from the lower passage 20, consequently cream cannot pass into the brush 29 from the tube 10.

When the brush is to be used, the cap is removed and the valve head turned ninety degrees from the positions shown in Figures 1 and 3 to those shown in Figures 2 and 4. In the latter, it will be seen, the two passages 27 and 20 are in communication and cream may now pass to the brush.

In other words, a simple ninety degrees movement closes the dispensing device or opens up a passage for the cream to the brush. During use, the flange 17 prevents water from running from the brush down over the hand of the user. After use, the valve is closed and the cap put on to lock the valve in closed position.

In the appended claims I wish it understood that the two parts, the base 15 and the member 19, together are called a base, and the two parts, the head 23 and the sleeve 24, together are called a brush holding valve member. Also that I reserve the right to make changes in the construction of the device without thereby departing from the scope of the claims.

I claim:

1. In a shaving brush device, a base having a dispensing passage, a valve head also having a dispensing passage, means for securing the said head to the said base, said head being capable of assuming two predetermined positions on the base in one of which the said two passages are in communication and in the other of which position the said two passages are non-communicating, means for locking the head and the base in non-movable relation when the said two passages are in non-communicating position and means for securing the device to a container.

2. In a shaving brush device, an adapter for securing the device to a container, a base secured to the adapter and having an offset passage, a valve head also having an offset passage, means for mounting said valve head on the base in rotatable relation, means for moving said head on the said base to cause the said two passages to register or non-register at will and a cap for locking the said head and base with their passages in non-registering positions.

3. In a shaving brush device, a dispensing base having a tooth, a base member therein having an offset dispensing passage and an overhanging annular flange, a sleeve having a tooth mounted to rotate on said base member and provided with an annular flange engaging under the flange aforesaid, a valve head secured to said sleeve and having an offset dispensing passage, a groove in said base member, a pin in said head adapted to

engage said groove, a cap adapted to engage the said two teeth when aligned for locking the said sleeve and head to the said base and base member with the said two passages in non-registering relation and means for securing the device to a container in dispensing relation thereto.

4. In a shaving brush device, a dispensing member having a dispensing passage, a head mounted on said member and having a dispensing passage, means for rotating the head on the dispensing member to cause the said two passages to register and for moving them into non-registering relation, a tooth on said member and on the said head, a removable cap for enclosing said member and for engaging the said two teeth to prevent the said two passages from registering and an adapter for securing said dispensing member to a container having a dispensing neck of a given size.

JAY WILL LYSONS.
